INVENTOR

Harry J. Trimble

UNITED STATES PATENT OFFICE.

HARRY J. TRIMBLE, OF CONEY ISLAND, NEW YORK.

SALT-CELLAR.

No. 922,978.

Specification of Letters Patent.

Patented May 25, 1909.

Application filed April 2, 1909. Serial No. 487,578.

To all whom it may concern:

Be it known that I, HARRY J. TRIMBLE, a citizen of the United States, and resident of Coney Island, in the county of Kings and 5 State of New York, have invented certain new and useful Improvements in Salt-Cellars, of which the following is a specification.

This invention relates to salt cellars, and the object thereof is to provide a highly sanitary article of the class specified which has no metallic parts that come in contact with the contents. A further object being to entirely eliminate the corrosion of the parts so common with articles of this class, especially 10 when used in sections where the air always carries more or less moisture. A still further object being to provide fastening means for the cover of the cellar which is simple and effective. A further object being to 15 provide an article of the class specified which will be comparatively simple in construction and inexpensive.

In the drawings:—Figure 1, is a side elevation of my improved salt cellar showing 20 the cover in position. Fig. 2, a section on the line 2—2 of Fig. 1. Fig. 3, a section taken on the line 3—3 of Figs. 1 and 2, and,— Fig. 4, a perspective view of a spring employed to fasten the cover to the body of the 25 cellar.

Like reference characters designate corresponding parts in the figures of the drawings illustrating my invention.

Referring to the drawings *a*, designates 30 the cellar body preferably of glass and *b*, the cover thereof preferably composed of glass. The body *a*, is provided with an annular flange *a*², having at one side thereof a socket *a*³, and the body *a*, is also provided at the 35 side thereof opposite the socket *a*³, with an upwardly directed lug or projection *a*⁴, having a rounded head *a*⁵, at the top thereof.

The cover *b*, in the form of construction shown, is provided with an annular depending flange *b*², and said flange *b*² is provided, on its inner face and at one side, with an inwardly directed rounded projection *b*³ which, when the parts are in their normal 40 position, enters the socket *a*³ and locks the cover *b*, to the body *a*, at one side. The cover *b*, is also provided with a recess *b*⁴, in the side opposite to the projection *b*³, and this recess is adapted to receive a spring member *c*. The spring member *c*, is preferably constructed of a flat piece of spring metal bent at its middle into a loop *c*², and

the free ends are then formed into diametrically ranging, diverging arms *c*³, and the free ends are then formed into feet or lugs *c*⁴, the purpose of which will be hereinafter 60 described. The cover *b*, is also provided, in the form of construction shown, with horizontal channels *b*⁵, which intersect the recess *b*⁴, and these channels *b*⁵, receive the feet *c*⁴, of the spring *c*, when said spring is placed 65 in operative position, as clearly shown in Figs. 1. and 3. of the drawings. The cover *b*, is also provided with the usual orifices *b*⁶, in the top thereof.

The cover is securely fastened to the body 70 of the cellar by means of the socket *a*³, projection *b*³, lug *a*⁴ and spring *c*, as will be readily understood. The projection *b*³, is first caused to enter the socket *a*³ when the cover is forced down at its opposite side and 75 the spring will be expanded over the head *a*⁵ of the lug *a*⁴, as clearly shown in Fig. 1.

Having fully described my invention, what I claim as new and desire to secure by Letters Patent is:—

1. In an article of the class described, a body member having an annular flange provided with a socket, a headed lug carried by said body member, a cover provided with means co-acting with said socket and said lug to fasten said cover to said body member.

2. In an article of the class described, a body member provided with a socket and a headed lug, a cover member having a projection adapted to enter said socket, and a spring carried by said cover member and adapted to coact with said headed lug to lock said cover member to said body member.

3. In an article of the class described, a body member having a socket at one side thereof and a headed lug at the opposite side, a cover member having an inwardly directed projection adapted to enter said 100 socket, a recess, a spring adapted to enter said recess, said spring being adapted to embrace said headed lug to lock the cover member to the body member.

Signed at New York in the county of 105 New York and State of New York this 31st day of March A. D. 1909.

HARRY J. TRIMBLE.
